UNITED STATES PATENT OFFICE.

JOHN W. JOHNSTON, OF STOCKTON, CALIFORNIA.

BANK-PROTECTING DEVICE.

Application filed April 13, 1926. Serial No. 101,690.

This invention relates to improvements in devices for protecting counter or window workers in banks and other similar mercantile houses from danger when an attempted hold-up of the workers behind the counter is staged.

The principal or fundamental objects of the invention, the advantages thereof, and the method of controlling the functioning of the structure are substantially the same as set forth in my co-pending application for patent, Serial No. 63,018, allowed March 19th, 1926, and hence a repetition of such objects is unnecessary herein.

The main object of the present invention is to provide protecting screen or shutter structures, in the form of units, one to cover the entire width of a worker's cage as well as the window itself; each unit as a whole being so constructed and arranged that it may be easily installed in any establishment whose counters, partition and grille work are already set up, and without having to mutilate or rearrange any of such permanent parts.

These objects I accomplish by means of such structure and relative arrangement of parts as will fully appear by a perusal of the following specification and claims.

In the drawings similar characters of reference indicate corresponding parts in the several views:

Fig. 1 is a top plan view of my improved protecting units installed in place.

Fig. 2 is an end elevation of the same.

Fig. 3 is a fragmentary enlarged transverse section taken on the line 3—3 of Fig. 1.

Fig. 4 is an enlarged end elevation of the device partly in section looking toward the other end of the structure from that shown in Fig. 2.

Fig. 5 is a cross section on the line 5—5 of Fig. 3.

Fig. 6 is a fragmentary longitudinal view of the curtain structure.

Fig. 7 is a fragmentary detail showing a catch for the bottom curtain-bar.

Referring now more particularly to the characters of reference on the drawings, the numeral 1 denotes the usual horizontal counter supported by a solid wall 2 extend-

ing to the floor, and having an upper wall form of grille-work 3 or similar arrangement extending thereabove, said grille-work being provided with a window 4 intermediate its ends. Transverse inwardly projecting partitions 5 divide the counter structure into a number of separated compartments or cages. This arrangement is standard in one form or other in most banks and the like, and I do not alter the same in any way.

My improved projecting apparatus for each cage comprises a pair of tubular members 6 mounted on the counter adjacent the junctions of the partitions 5 with the front wall 3. Mounted on top of the tubular members are tubular caps 7 having brackets 8 projecting inwardly from the wall 3. Turnably mounted on anti-friction bearings 9 in the brackets and extending therebetween is a shaft 10 on which is fixed a drum 11.

Mounted in the drum is a flexible curtain 12, one end of which is fixed on the drum and the other end projects at its edges into vertical slots 13 cut in the adjacent faces of the members 6 and 7. These slots extend from the bottom of the members 6 to a point intermediate the ends of the members 7, and terminate at the inner sides of the latter in the form of relatively deep mouths 14, so as to receive the curtain with equal facility, regardless of the winding or unwinding of the curtain from the drum, which is fixed.

The curtain is preferably formed of a number of horizontal steel bars or slats 15 placed closely together. These bars are connected together in flexible relation by flexible cables 16 or the like which are preferably attached to the individual bars by clamping clips 17 applied to the ends of the bars, as shown in Fig. 6. The curtain is guided properly into the mouths of the slots without rubbing contact with the walls by means of rollers 18 mounted on the brackets 8 and projecting under the curtain adjacent the slots.

The lowermost bar 15^a of the curtain has a length sufficient to project through the slots 13 to adjacent the opposite sides of the tubular members while the other bars terminate short of the bar 15^a and have a length only sufficient to enable them to be guided in the

slots. Substantial coil springs 19 mounted in the caps 7 bear down on the extended ends of the bars 15^a.

In order to normally maintain the curtain wound on the drum, the lower bar 15^a adjacent the top of the slots and the spring 19 fully compressed, I provide the following structure:

A ratchet wheel 20 is mounted on the shaft 10 at one end thereof. This ratchet wheel is normally engaged by a spring pressed pawl 21 mounted on the adjacent bracket 8. This pawl is released at will, to release the drum and allow the springs 19 to function to lower the curtain, by means of a rod 22 applied to an arm 21^a extended from the pawl 21. This rod extends thence through the counter 1 to a connection with a foot lever or pedal 23 mounted on the floor under the counter. This pedal arrangement, for operating the various curtain units, is preferably the same as that shown in the aforementioned previous application, so that any unit may be operated independently of any others, or all 25 may be operated simultaneously from any one point.

In order to break the shock of descent of the curtain when adjacent the counter I place spiral telescopic springs 24 in the members 6 at the bottom thereof to engage the lower curtain bar 15^a. The springs 24 being telescopic do not interfere with the lowering of said bar to a point immediately adjacent the counter, the resistance of said springs 35 being less than the combined weight of the curtain and the pressure of the springs 19. In order to enable the curtain to be easily raised after it has been lowered, I provide a downwardly depending lever 26 which is 40 turnably mounted on the shaft 10 outwardly of the ratchet wheel 20. Said lever has a spring pressed pawl 27 which engages a ratchet wheel. It will therefore be seen that a reciprocating movement of the lever will 45 cause a rotation of the ratchet wheel and drum in a direction to cause the curtain to be wound onto the drum, the reverse rotation of the drum when the lever is retracted being prevented by the engagement of the 50 relatively fixed pawl 21 with the ratchet wheel 20.

To cause the pawl 27 to be disengaged from the ratchet wheel when the pawl 21 is disengaged therefrom, an extension 28 is 55 provided with said pawl 27, which extension projects into the path of downward movement of the arm 21^a, such movement of said arm thus causing both pawls to be disengaged from the ratchet wheel simultaneously. To maintain the lever in fixed position when not in use, a detachable hook connection 29 is provided between the lever and the adjacent standard 6. In order that the apparatus may present a neat appearance 60 and one which will be easily kept clean, the

drum and if necessary the ratchet and pawl mechanism are preferably surrounded by a housing 30 which is attached to the brackets 8.

The springs 19 should be of sufficient 70 strength to cause the curtain to descend very rapidly, and to maintain the curtain at its lowermost position with a certain pressure besides the actual weight of the curtain.

To cause the curtain to be positively maintained at such lowermost position however, the lower bar 15^a is provided with inwardly projecting lugs 31 near the members 6. Each lug, when the curtain is lowered to its fullest extent, automatically engages a spring 80 pressed releasable pawl 32 mounted in connection with the adjacent member 6.

From the foregoing description it will be readily seen that I have produced such a device as substantially fulfills the objects of the 85 invention as set forth herein.

While this specification sets forth in detail the present and preferred construction of the device, still in practice such deviations from such detail may be resorted to as do not form a departure from the spirit of the 90 invention, as defined by the appended claims.

Having thus described my invention what I claim as new and useful and desire to secure by Letters Patent is:

1. A device for protecting an opening comprising a curtain mounted in connection therewith to cover the same and normally clear of said opening, spring means tending to move the curtain to a covering position, said spring means having a strength sufficient to impel the curtain to a closing position but insufficient to maintain it in such position, releasable means normally preventing the spring means from functioning, and releasable catch means to engage and positively hold the curtain in covering position after the spring means has initially acted to move the curtain to such position.

2. A device for protecting an opening comprising a flexible curtain to cover the opening, a drum mounted in connection with the opening beyond one side thereof and on which the curtain is normally wound to be clear of said opening, means tending to unwind the curtain from the drum and rotate the latter, a ratchet wheel mounted on the drum, a lever turnably mounted relative to and concentric with the drum adjacent the sprocket wheel, a pawl mounted on the lever and normally engaging the ratchet wheel, said pawl and ratchet wheel being arranged to cause the drum to be rotated in a curtain winding direction with the movement of the lever in one direction, another pawl fixed relative to the drum independent of the lever and also normally engaging the ratchet wheel, manually operated means for releasing said last named pawl, and means between the pawls for causing the lever pawl

to be released from the ratchet wheel when said other pawl is released therefrom, without causing said other pawl to be released when the lever is manipulated to actuate the 5 pawl thereof.

3. A structure as in claim 2, said last named means comprising an extension projecting from the first named pawl, and an arm projecting from the second named pawl

and overhanging the extension, said extension and arm being so disposed that when the second named pawl is disengaged from the ratchet wheel the arm thereof will bear against the extension to move the pawl attached thereto clear of the ratchet wheel. 10 15

In testimony whereof I affix my signature.

JOHN W. JOHNSTON.
